UNITED STATES PATENT OFFICE.

CLIFFORD J. TOMLINSON, OF WEST ALLIS, WISCONSIN, ASSIGNOR TO ALLIS-CHALMERS MANUFACTURING COMPANY, OF MILWAUKEE, WISCONSIN, A CORPORATION OF DELAWARE.

PULVERIZER.

1,331,968.

Specification of Letters Patent. Patented Feb. 24, 1920.

Application filed December 22, 1915. Serial No. 68,932.

To all whom it may concern:

Be it known that I, CLIFFORD J. TOMLINSON, a citizen of the United States, residing at West Allis, in the county of Milwaukee 5 and State of Wisconsin, have invented a certain new and useful Improvement in Pulverizers, of which the following is a specification.

This invention relates to improvements in 10 the construction of impact pulverizers and especially to improvements in the construction of hammers or bails for such pulverizers.

An object of the invention is to provide 15 a pulverizer hammer or bail which is simple in construction, efficient in operation, and in which the portion which is subjected to excessive wear may be readily removed and renewed. One of the more specific objects 20 is to provide a simple and strong hammer or bail comprising a pair of spaced radial arms and a cross-bar detachably secured to corresponding ends of said arms. Another object is to provide simple and efficient means 25 for detachably securing the cross-bar to the arm ends. A further object is to provide a suspension device for the bail, which will also serve to lock the means for securing the bail arms to the cross-bar, in place.

30 The present invention is an improvement over the device disclosed in application Serial No. 790,366, filed Sept. 15, 1913, which application claims broadly some of the novel features shown herein.

35 A clear conception of an embodiment of the invention may be had by referring to the drawing accompanying and forming a part of this specification, in which like reference characters designate the same or 40 similar parts in the various views.

Figure 1 is a transverse vertical section through a rotary impact pulverizer having the improved bails applied.

Fig. 2 is an enlarged, part sectional elevation of one of the hammers or bails, showing the same secured to a fragment of the suspension means.

Fig. 3 is an enlarged end elevation of one of the hammers or bails.

50 Fig. 4 is a transverse section through the cross-bar of one of the bails showing also an elevation of one of the arms, the section being taken along the line IV—IV of Fig. 2.

The rotary impact pulverizer, see Fig. 1, 55 comprises, in general a circular series of

rapidly revoluble radial hammers or bails suspended from a shaft 2, and a main casing 1. The casing 1 is provided with a feed inlet 7 through which the material to be pulverized is delivered into the path 60 of the revolving bails. The upper portion of the casing 1 adjacent the path of the bails, is provided with liners 6 having involute impact surfaces so located that they will tend to return the material projected 65 thereagainst, into the path of the moving bails. The lower portion of the casing 1 is provided with a series of grate bars 10 having passages therebetween adapted to deliver the reduced material to the discharge 70 opening 8. The shaft 2 is mounted in bearings in the casing 1 in the usual manner and has a suspension member 4 secured thereto by means of a key 3 or other suitable fastening device. The suspension member 4 has end surfaces 18 forming abutments spaced apart longitudinally of the axis of rotation of the member 4. The hammers or bails are suspended from the member 4 by means of pivot pins 5 which are 75 locked against end displacement by any suitable means such as set screws 17, see Fig. 2.

Each of the hammers or bails comprises a pair of substantially radial arms 9 and a longitudinally recessed cross-bar 13. The 85 inner extremities of the arms 9 are provided with inner surface portions 19 which coöperate with the surfaces 18 of the suspension member 4, to prevent displacement of the arms 9 toward each other. The 90 cross-bar 13 is detachably secured to the outer enlarged ends 11 of the arms 9, by means of projections 12 formed two on each arm 9 and extending transversely of the shaft 2. The projections 12 form abutments facing the shaft 2, which engage substantially parallel abutments or projections 15 formed on opposite sides of the longitudinal recess 14 of the cross-bar 13. The opposite ends of the cross-bar 13 are provided 100 with abutments or walls 16 the inner surfaces of which form stops engageable with the outer surface portions 20 of the arms 9. The enlargements 11 at the ends of the arms 9 provide the requisite strength and increase 105 to a maximum the surfaces of engagement between the elements.

In order to assemble a bail, the arms 9 are first secured to the cross-bar 13 by inserting the headed ends 11 in the central 110

portion of the recess 14 and sliding the arms 9 over until their outer surface portions 20 engage the end walls 16. After the arms 9 have been thus positioned relatively to the 5 cross-bar 13, their inner ends are arranged with the openings of the arms 9 in alignment with the adjacent opening in the suspension member 4 and with their inner surface portions 19 adjacent the suspension 10 member end surfaces 18, after which the suspension pin 5 may be inserted and locked by means of the set screw 17.

The insertion of the pin 5 positively locks the bail elements together and prevents displacement of the headed ends 11 of the arms 9 from within the recess 14 of the cross-bar 13. It will be noted that the abutment surfaces 18 of the suspension member 4 positively prevent displacement of the arms 9 15 toward each other while the abutments or walls 16 of the cross-bar 13 positively prevent displacement of the arms 9 away from each other. By providing two oppositely disposed like projections 12 on each of the 20 arms 9 and otherwise symmetrically forming these arms they are subjected only to forces acting radially of the shaft 2, thus avoiding bending strains on the arms such as might result from unsymmetrical formation 25 of the same. The provision of the recess 14 and of a connecting means between the arms 9 and the cross-bar 13 lying entirely within the said recess, effectively prevents injury of the connecting means. The 30 inwardly extending projections at the outer extremities of the arms 9 which overhang the suspension member 4, form weights which when acted upon by centrifugal force prevent displacement of the outer extremities 35 of the arms 9 away from the walls 16, thereby insuring maintenance of the connections between the arms 9 and the cross-bar 13. The bail elements may be readily formed either by casting or forging and require very 40 little finishing.

It should be understood that it is not desired to be limited to the exact details of construction shown and described, for obvious modifications will occur to a person 50 skilled in the art.

It is claimed and desired to secure by Letters Patent,—

1. In combination, a suspension member 55 rotatable about an axis and having abutment surfaces spaced apart longitudinally of said axis, a pair of arms secured to said member and radiating from said axis, each of said arms being symmetrical with reference to a central plane transverse to said 60 axis and said arms having inner portions coöperable with said abutment surfaces to prevent displacement of said arms toward each other, and a bar secured to and connecting said arms at their extremities remote 65 from said axis, said bar having inner

walls spaced apart longitudinally of said axis and said arms having outer side portions coöperable with said bar walls to prevent displacement of said arms away from each other.

2. In combination, a suspension member 70 rotatable about an axis and having abutment surfaces spaced apart longitudinally of said axis, a pair of arms secured to said member and radiating from said axis, said arms having inner portions coöperable with said abutment surfaces and said abutment surfaces constituting the sole means for preventing motion of translation of said arms toward each other, and a bar secured to and connecting said arms at their extremities remote from said axis, said bar having inner walls spaced apart longitudinally of said axis and said arms having outer side portions coöperable with said bar walls to prevent displacement of said arms away from each other.

3. In combination, a suspension member 75 rotatable about an axis and having abutment surfaces spaced apart longitudinally of said axis, a pair of arms secured to said member and radiating from said axis, said arms having inner side portions coöperable with said abutment surfaces to prevent displacement of said arms toward each other, 80 and a bar secured to and connecting said arms at their extremities remote from said axis, said bar having inner walls spaced apart longitudinally of said axis and said arms having outer side portions coöperable with said bar walls to prevent displacement of said arms away from each other.

4. In combination, a suspension member 85

rotatable about an axis and having abutment surfaces spaced apart longitudinally of said axis, a pair of arms secured to said member and radiating from said axis, said arms having inner side portions coöperable with said abutment surfaces to prevent displacement of said arms toward each other and said arms each having an outer side portion and a pair of transverse projections at its extremity remote from said axis, and a 90 bar having transverse projections and inner walls spaced apart longitudinally of said axis, said arm projections being engageable with said bar projections to secure said bar to said arms and said outer side portions of said arms being coöperable with said spaced bar walls to prevent displacement of said arms away from each other.

5. In combination, a suspension member 95 rotatable about an axis and having opposite surfaces spaced apart longitudinally of said axis, a pair of parallel arms secured to said member and radiating from said axis, said arms having inner side surfaces coöperable with said member surfaces to prevent dis- 100

- placement of said arms toward each other and said arms each having an outer side surface and a pair of parallel transverse projections at its extremity remote from said 5 axis, and a bar having parallel transverse projections and inner surfaces spaced apart longitudinally of said axis, said arm projections being engageable with said bar projections to secure said bar to said arms and 10 said outer side surfaces of said arms being coöperable with said spaced bar surfaces to prevent displacement of said arms away from each other.
6. In combination, a cross-bar having a 15 recess, an arm formed for attachment to said cross-bar within said recess, said arm having a projection extending from one side of said
- arm, and means for operating said arm so that said projection aids in preventing releasing displacement of said arm along said 20 recess.
7. In combination, a cross-bar having a longitudinal recess therein, a pair of arms spaced longitudinally of said bar and secured to said bar within said recess, said 25 arms having projections extending from said arms on adjacent sides thereof, and means for operating said arms so that said projections aid in preventing displacement of said arms along said recess. 30

In testimony whereof the signature of the inventor is affixed hereto.
